ABSTRACT

A disc-sealed electron discharge tube wherein the grid electrode or electrodes and a hollow anode each have a flat surface provided with an annular slot for the passage of electrons, radial spoke-like elements extend across said slots, the radial elements in each electrode being aligned with the radial elements in the other such electrodes, and wherein means are provided to magnetically focus the hollow electron beam.

DISC-SEALED ELECTRON DISCHARGE TUBES

BACKGROUND OF THE INVENTION

1. Field of the Invention

This invention relates to disc-sealed electron discharge tubes which are capable of high-power output at ultra-high frequencies, of the kind comprising an annular metal-capillary cathode having a central non-emissive area of lower temperature than the emission temperature prevailing in the emissive area and responsible for producing a hollow electron beam, one or more grid electrodes and an anode which has an annular active end area to receive the electron current.

2. Description of the Prior Art

The present invention is particularly useful for the generation of ultra-frequencies of the order of a few GC/sec and is applicable both to triode and tetrode types of electron tubes. The quality and quality factors of disc-sealed tubes, both of triode and tetrode constructions, have undergone considerable improvement in recent years, in terms of gain, service life and reliability. However, at such high frequencies as those referred to above, the possibilities which are open to generate high powers using grid-control tubes are limited, in particular by the increase in size of the overall system. Because the dimensions must be kept as small as possible in grid-control tubes compared with the wave length, a disadvantage arises in that a limit is reached which, in power output tubes, is set in particular by the grid loading of the tube. This makes it necessary to change from the cross-braced type grid to some other type of system. A further increase in power can then only be achieved by increasing the current density and the operating voltages, while at the same time retaining the major tube dimensions. This kind of procedure, however, encounters a limitation in terms of the thermal loading capacity of the anode material.

A disc-sealed tube having a dispenser metal-capillary cathode which has an annular emissive area and produces a hollow electron beam is well known in the art, but in this type of tube the grid electrode is designed to extend over the full circular area as a cross-braced grid, and the active part of the solid anode is designed as a flat reflector anode. In the known construction of a disc-sealed tube, the output power is limited by the specific loading capacity of both the grid electrode and the anode.

SUMMARY OF THE INVENTION

An object of the present invention, therefore, is to provide a power increase by increasing the discharge current density, by special design of the critical electrodes, and by additional control of the electron beam, such as may be effected by magnetic focusing.

The invention resides in the provision of a disc-sealed electron discharge tube of the type mentioned above, wherein the grid electrode, or electrodes, and a hollow anode each have a flat surface provided with an annular slot for the passage of electrons. Radial spoke-like elements extend across the slots to support the central portions of the electrodes, the radial spoke-like elements in each electrode being aligned with the radial spoke-like elements of the other electrode or electrodes. Further, means are provided for magnetically focusing the hollow electron beam.

When using a hollow anode, the beam energy can be distributed over a substantially larger area by suitable additional focusing measures. The anode therefore preferably comprises a hollow cylinder which extends beyond the surface and provided with an annular slot, and the outer wall of which cylinder is provided with a convection cooler.

In order to dissipate the grid loss power by conduction and heat transfer, e.g., by utilizing cooling air, it is preferable for the grid electrode, or electrodes, to have a cup-shaped form, the controlling grid surface being substantially solid for reasons of stability and good thermal conductivity, so that only an annular portion thereof, comprising radially extending grid elements, actually serves as the active grid electrode. For this purpose, and to facilitate and make possible suitable magnetic focusing, parts of the grid and anode electrodes which are not directly involved in the discharge, and neighboring parts of the discharge vessel wall, in the neighborhood of the focusing magnet or coil, are preferably made of magnetic material.

In order to exploit the full power capacity of the tube, and to provide an easily exchangeable component which can be used in an amplifier, it is advantageous to make the tube part of a single unit including an associated tank circuit, a cooling arrangement and a magnetic focusing arrangement.

BRIEF DESCRIPTION OF THE DRAWING

Other objects, features and advantages of the invention, its organization, construction and operation will be best understood from the following detailed description of a preferred embodiment of the invention taken in conjunction with the accompanying drawing on which a single FIGURE of a disc-sealed triode is illustrated in a generally elevational cross sectional showing. Components which do not form an essential part of the invention are left unmarked or are omitted from the drawing.

DESCRIPTION OF THE PREFERRED EMBODIMENT

A metal-ceramic tube is illustrated in the drawing as a disc-sealed triode having an annular metal-capillary dispenser cathode 1 of low operating temperature. The cathode comprises a ring-shaped porous emission substance carrier disc 2 which covers and closes off a correspondingly shaped dispenser and forms the emissive cathode body. Beneath the cathode body and inside an associated carrier foil cylinder 3, there is arranged a heater 4 which is, for example, cemented in position. In the central hollow cylinder of the cathode body 2, and at the end facing the grid electrode 5, there is provided a radiation protector or foil 2' which takes the form of an outwardly dished sheet metal cap so that the amount of heat radiated onto the grid electrode 5, and particularly the central area thereof, from the cathode-heating arrangement, is kept small.

The grid electrode 5 is arranged above the cathode at a short distance from the emissive area 2, together with its mounting, essentially comprises a rigid cupped sheet metal cylinder, the active grid structure of which is in the end face where it takes the form of an annular slot 6 which is crossed by radially-disposed grid elements. The grid elements preferably consists of very narrow spokes, e.g., of flat rectangular cross-section. The solid central part of the grid electrode, which is

made of a material having good thermal conductivity, provides an additional heat balance in the neighborhood of the grid elements.

When the tube is constructed as a tetrode, an additional, cupped grid electrode is provided beyond the control grid 5 to act as a screen grid. By providing cooling fins on the connecting portion of this electrode, highly effective heat dissipation from the screen grid is achieved.

The hollow anode 7 comprises a cupped hollow cylinder closed off at its open end by a substantially rigid diaphragm 8 which is interrupted by an annular slot 9 which may be provided with radial spokes for stiffening. When the tube is in operation, it is at this diaphragm that the high-frequency energy carried by the hollow electron beam is picked off. Any stiffening spokes in this annular diaphragm and the grid elements of the control grid or control and screen grids, are aligned with each other so that they are virtually completely untouched by the hollow electron beam emitted from the annular area of the cathode and focused by a magnetic field. The solid parts of the anode end face, thus remain untouched by the hollow electron beam as the latter passes through the tube in the course of its discharge, i.e., the end face experiences virtually no electron bombardment, while behind the end face the hollow beam is fanned out radially and is incident upon the large internal wall area of the cylinder.

The focusing of the hollow electron beam is effected either as shown by a coil 11, which is encapsulated in the magnetic material, or by a corresponding permanent magnet ring. The magnetic flux is conducted by way of the magnetic material 12 in such a way that the requisite field is developed, or is present, in the discharge space.

The cooling of the anode 7 is effected with the help of a multi-passage air cooler 13 and an air distributor 14 associated with the grid electrodes, preferably by using an air stream directed onto the junction or connection points.

The tube is made to form part of a single unit together with the cooling device 13, 14, and an associated tank circuit 15 provided with a corresponding tuning device 16.

In the metal-ceramic tube, individual ceramic cylinders 17, 18 are responsible for insulating anode and cathode circuits, respectively, and after the required metalizing for connection are connected with the relevant metal cylinders or electrode parts, for example by brazing.

All of the parts in the neighborhood of the magnetic focusing components are constructed of magnetic material, unless requirements dictate otherwise.

The design of a tube in accordance with the present

invention has considerable advantages because the high current density achieved makes it possible to obtain extremely steep gain characteristics and therefore high gains. Critical factors in achieving this result are the magnetically focused hollow electron beam, the enlarged impact area on the hollow anode and the relatively solid grid electrode with its inner part of a material having good thermal conductivity.

Although we have described our invention by reference to a specific preferred embodiment thereof, many changes and modifications of our invention may become apparent to those skilled in the art without departing from the spirit and scope of the invention. We therefore intend to include within the patent warranted hereon all such changes and modifications as may reasonably and properly be included within the scope of our contribution to the art.

What we claim is:

1. A disc-sealed electron discharge tube, comprising: a cathode for emitting a hollow electron beam; a hollow anode including a flat surface having an annular slot for passing the hollow electron beam and an arcuate surface for receiving the hollow electron beam; and at least one grid electrode disposed in the path of said hollow electron beam and including a solid central part, means defining an annular slot for passing the hollow electron beam, said flat surface of said anode and said means defining an annular slot of said grid each including a plurality of radial elements extending spoke-like across said annular slots and aligned with the radial elements of each other; and means for magnetically focusing the hollow electron beam to fan out the beam only within said hollow anode.

2. A tube according to claim 1, wherein said hollow anode comprises a hollow cylinder which extends beyond said flat surface, and convection cooling means associated with said hollow cylinder.

3. A tube according to claim 1 wherein said grid electrode is cup-shaped and has a surface disposed about said cathode and extending away from said anode.

4. A tube according to claim 1 comprising a screen grid having a solid central portion, means defining an annular slot therein for passing the hollow electron beam, radial elements extending across said annular slot and cooling fins extending from said screen grid.

5. A tube according to claim 1, wherein portions of said electrodes and portions of said discharge tube, other than said cathode, consisting of magnetic material.

6. A tube according to claim 1 comprising an associated tank circuit and a cooling arrangement constructed together with said magnetic focusing means and said tube as a single unit.
